UNITED STATES PATENT OFFICE.

DAVID W. WATSON, OF SYRACUSE, NEW YORK, ASSIGNOR TO EUGENE WEST, OF SAME PLACE.

DESIGN FOR KNIT FABRIC.

SPECIFICATION forming part of Design No. 34,952, dated August 13, 1901.

Application filed July 9, 1901. Serial No. 67,679. Term of patent 7 years.

To all whom it may concern:

Be it known that I, DAVID W. WATSON, a citizen of the United States, residing at Syracuse, county of Onondaga, State of New York, 5 have invented and produced a new and original Design in Knit Fabrics, of which the following is a specification, reference being had to the accompanying drawing, forming a part thereof, in which I show a portion of the fabric setting forth the design complete.

As shown in the drawing, the leading or material feature of my design consists in a series of rows of substantially parallel lace

stitches *a*, united to the main body of the knit fabric *b* by transverse threads *c*. 15

Having fully described my invention, what I claim, and desire to secure by Letters Patent, is—

The design for knit fabric substantially as herein described and shown. 20

In witness whereof I have hereunto set my hand this 5th day of July, 1901.

DAVID W. WATSON.
